MUCKING MACHINE FOR MINE SHAFTS

William E. Kindsvater, Paige, Idaho

Application January 27, 1947, Serial No. 724,545

5 Claims. (Cl. 214—120)

1

This invention relates to a mucker and it is one object of the invention to provide a mucker of such construction that it may be lowered into a shaft and muck, such as rock and dirt, at the bottom of the shaft may be very easily scooped therefrom and hoisted out of the shaft.

Another object of the invention is to provide a mucker which consists briefly of a scoop connected with a cable by means of which the scoop is drawn along the bottom of the shaft for filling and then hoisted into position for dumping muck from the scoop into a hopper from which the muck may be discharged into a bucket and the bucket hoisted from the shaft.

Another object of the invention is to provide a scoop shaped as a drum and formed with a longitudinally extending inlet having a lip along its lower edge so that as the scoop is drawn forwardly muck will be guided into the scoop.

Another object of the invention is to provide a barrel-shaped scoop having a lip along the lower edge of its inlet opening so formed that after the scoop has been filled the lip may be engaged with vertical tracks or rails in the shaft and guided as it is drawn upwardly into position for dumping muck into a hopper.

Another object of the invention is to provide a set of rails or tracks having upper end portions so formed that when the barrel-shaped scoop reaches upper ends of the rails it will be rotated to a dumping position over the trough.

Another object of the invention is to provide a scoop having means removably associated with it to engage a bail by means of which the scoop is drawn forwardly and prevent rotation of the scoop while it is being filled with muck.

Another object of the invention is to provide an improved mucker which is simple in construction, easy to install in a shaft being dug, and very easy to operate.

The invention is illustrated in the accompanying drawings wherein:

Fig. 1 is a view partially in vertical section and partially in elevation and showing the improved mucker in position for use in a shaft.

Fig. 2 is a view similar to Figure 1 taken at right angles thereto.

Fig. 3 is a perspective view of the barrel shaped scoop.

Fig. 4 is a side view showing the upper portion of the tracks upon an enlarged scale.

Fig. 5 is an end view of the scoop.

Fig. 6 is a perspective view showing the hopper carried by a portion of the frame erected in a shaft and a bucket in position to be filled by muck discharged from the hopper.

The mucking apparatus constituting the subject matter of this invention is used for removing rock, dirt, and the like from the bottom of a mine shaft or other deep excavation. Such a shaft is shown in Figures 1 and 2 and indicated by the

2

numeral 1 and as the shaft is deepened timbers are set up in the shaft to form a frame 2 by means of which the walls of the shaft are braced and prevented from caving in. The frame is progressively deepened as the shaft is dug and as muck is removed from the bottom of the shaft it is hoisted upwardly through the shaft and the bracing frame for the shaft in a bucket 3 having a bail 4 to which a hoisting rope is attached.

10 A barrel-shaped scoop or drum 5 is used for removing muck 6 from the bottom of the shaft. This scoop is specifically illustrated in Figures 3 and 5 and referring to these figures it will be seen that the scoop has a barrel-shaped body provided with heads 7 at its ends and having its annular wall formed with a longitudinally extending opening 8 from the lower edge 9 of which projects a lip 10 located midway the length of this edge. A yoke 11 which is formed of strong metal and provided with arms 12 is disposed in straddling relation to the scoop with its arms overlapping the heads 7 of the scoop and pivotally connected therewith by pins 13 so that when the scoop is pulled forwardly the scoop may be tilted relative to the yoke by a workman grasping the handles 14 of the scoop and the lip 10 caused to enter the muck 6 and direct rock or dirt into the scoop through the inlet opening 8. A stop bar 15 extends longitudinally of the scoop in front of the opening 8 and is of such length that its end portions will overlap the side arms 12 of the yoke. Arms 16 extend from end portions of the stop bar toward the scoop and are removably engaged through brackets or straps 17 secured to the heads of the drum. Therefore when the stop bar is in place its end portions will overlap the side arms of the yoke and serve very effectively to limit pivotal movement of the yoke and the drum relative to each other and pressure exerted 20 against the lip 10 as the drum is drawn forwardly along the bottom of the shaft will be prevented from turning the drum to a position in which muck can not enter the drum through the opening 8. An eye bolt 18 projects forwardly from the yoke and to this eye bolt is secured an end of a rope or wire cable 19 by means of which the scoop is drawn forwardly when the cable is engaged with a pulley 20 carried by a block 21 and pull is exerted to draw the cable upwardly through 25 the shaft. The upper portion of the cable may be wound about a hoisting spool or upward pull exerted upon the cable in any other manner desired. After the drum 5 has been pulled forwardly to a position close to the pulley, and the drum thus filled with muck, the cable is detached from the pulley and when upward pull is again exerted upon the cable the drum will be drawn upwardly through the shaft and the frame 2. Before upward pull is exerted upon the cable to 30 draw the scoop upwardly through the shaft the arms of the stop bar are withdrawn from the

brackets 17 and the handles 14 withdrawn from the sockets 22 into which they fit and the scoop turned from a position in which a head of the scoop is presented toward track bars or rails 23 to a position in which the annular wall of the scoop will bear against these rails. The weight of the muck in the scoop will cause the scoop to turn about the pivots 13 to a position presenting the opening 8 at the top of the scoop and there will be no danger of the rock and other muck spilling out of the scoop as the scoop is drawn upwardly through the shaft. Metal strips 24 and 25 which are mounted along front and rear faces of the track bars or rails and these strips have their upper portions projecting upwardly from the track bars as shown in Figures 4 and 6. The upwardly projecting portions of the rear strips 25 bear against the outer face of a side wall of a hopper 26 having a downwardly extending spout or chute 27, and referring to Figures 1 and 6 it will be seen that the upper end of the chute is formed with a recess 28 to receive a horizontally extending beam of the frame 2 when the hopper and its spout are mounted in the frame with the lower end of the spout resting upon a horizontal beam under the beam which fits into the recess 28. When the door at the lower end of the chute is opened muck dumped into the hopper and passing downwardly through the chute will be discharged from the chute and drop into the bucket 3 placed upon the bottom of the shaft 1 in position under the lower end of the chute. The upper portions of the strips 24 are bowed longitudinally to form arcuate guides 33 which project forwardly from the vertical plane of the track bar 23 and then extend rearwardly toward upper ends of the strips 25 and have their upper ends bent to form forwardly curving hooks 31 which are welded to upper ends of the strips 25, as shown at 32 in Figure 4. When the scoop is drawn upwardly along the track 23, with its annular wall resting against the strips 24, and passes upwardly along the guides 33 until it reaches the hooks 31. The drum rolls rearwardly as it approaches the hooks and the hooks will pass through the opening 8 of the drum at opposite sides of the lip 10 and continued upward pull upon the cable 19 will cause the scoop to be turned over the track into position over the hopper, as shown in Figure 2, and rock and other muck in the scoop will be discharged from the scoop and drop into the hopper. The scoop will then be lowered to the bottom of the shaft 1 for another filling and again drawn upwardly and dumped. This will be continued until the shaft has been dug to a desired depth, it being understood that as the shaft is deepened timbers will be added at the bottom of the frame 2 and the hopper and its chute or spout moved to the bottom of the frame.

Having thus described the invention, what is claimed is:

1. In a mucking apparatus, the combination with a frame erected in a vertical shaft being dug, a hopper carried by said frame and having a depending discharge chute, a track extending vertically in the shaft with its upper portion disposed along a wall of the hopper, said track having transversely spaced rails having hooks at their upper ends, a scoop having an inlet across its front, a yoke carried by said scoop and projecting forwardly therefrom, and a cable extending vertically in the shaft and having its lower end connected with the yoke, said cable constituting means for drawing the scoop forwardly in a filling

motion and then upwardly along the track, and the hook at the upper end of the track constituting means for engaging through the inlet of the scoop and causing the scoop to tilt over the upper end of the track to a dumping position over the hopper.

2. The structure of claim 1 wherein the track consists of transversely spaced track bars and strips extending along front and rear faces of the track bars and projecting upwardly therefrom, said strips projecting upwardly from the hopper, the upwardly projecting portions of the front strips being bowed longitudinally to form forwardly projecting guides for engagement by the scoop as it moves upwardly along the track, the upper extremities of the front strips being curved longitudinally and forming hooks welded to upper ends of the rear strips and having their lower portions merging into the bowed guides and their upper end projecting forwardly from the rear strips in position for engaging through the inlet of the scoop and causing turning of the scoop to a dumping position.

3. The structure of claim 1 wherein the scoop has a lip projecting forwardly midway the length of the lower edge of its inlet in position to have digging contact with muck at the bottom of the shaft as the scoop is drawn forwardly, the lip also serving as means for engaging between side rails of the track and grinding upward movement of the scoop along the track.

4. The structure of claim 1 wherein the yoke has a main bar extending longitudinally of the scoop in forwardly spaced relation to the inlet of the scoop and side arms extending rearwardly and pivoted to ends of the scoop, and an abutment removably carried by the scoop for engaging across the side arms of the yoke and limiting tilting movement of the yoke and the scoop relative to each other.

5. The structure of claim 1 wherein the yoke has a main bar extending longitudinally of the scoop in forwardly spaced relation to the inlet of the scoop and side arms extending rearwardly and pivoted to ends of the scoop, brackets carried by ends of the scoop, and an abutment bar over the yoke extending longitudinally thereof with its ends overlapping the side arms of the yoke, said abutment bar having rearwardly extending arms overlapping ends of the scoop and removably fitted through the brackets whereby the abutment bar may be removed from the scoop and allow the scoop to turn to a position presenting its inlet upwardly as the scoop is drawn upwardly along the track.
